CHARLES R. TOWLE, OF HAVERHILL, MASSACHUSETTS, ASSIGNOR OF ONE-HALF TO
HERMAN E. LEWIS, OF HAVERHILL, MASSACHUSETTS.

SHOE-SHANK-FORMING TOOL.

1,408,913.

Specification of Letters Patent.

Patented Mar. 7, 1922.

Application filed August 17, 1921. Serial No. 492,934.

To all whom it may concern:

Be it known that I, CHARLES R. TOWLE, a citizen of the United States, and a resident of Haverhill, county of Essex, State of Massachusetts, have invented an Improvement in Shoe-Shank-Forming Tools, of which the following is a specification.

In the manufacture of turned shoes it is frequently desired to shape the shank portion 10 of the sole so that each side portion will slope somewhat sharply from the middle longitudinal line of the shank portion, for the purpose of stiffening this portion, after the manner that sheet metal is stiffened by corrugation. In the trade, shoes thus formed are said to have a "cottage shank".

The operation of thus shaping the shank is performed as a part of the beating out 20 operation, which, with turned shoes is usually a hammering operation, and, in attempting to form a "cottage shank" with a hammer, considerable difficulty has been encountered, due to the fact that, when the 25 operator hammers on one side of the shank, near the edge, or presses thereon with a rub stick, the opposite portion will spring up from the last, so that an effective formation thereof is not secured.

The object of my invention is to provide 30 a form of hand implement with which the operation of shaping the shank of the sole of a turned shoe may be rapidly, effectively and satisfactorily performed.

I accomplish this object by providing a 35 form of implement which preferably consists of a block of wood formed to provide a face at one end, which is adapted to be struck with a hammer, and a pair of divergently extending faces at the opposite end, 40 adapted to bestride the shank and having convexly curved faces arranged for simultaneous engagement with opposite shank-edge-portions, so that the sole may be bent 45 sharply over a longitudinally extending rib on the middle of the shank stiffener and the shank-edge-portion may be permanently stretched or lengthened, so as to conform closely with the shank portion of the last.

For a more complete disclosure of the 50 invention reference is made to the accompanying drawing in which:

Fig. 1 is a side elevation of a tool embodying my invention.

Figs. 2 and 3 are central longitudinal

sectional views, at lines 2—2 and 3—3, respectively, of Fig. 4.

Fig. 4 is a plan view of the work engaging end of the tool.

Figs. 5 and 6 are sectional views of the 60 shank portion of a shoe on a last, with the tool in operative position.

Fig. 7 is a sectional view, at line 7—7 of Fig. 6.

As shown in the drawing I provide a 65 rounded block *a*, of hard wood, of a size adapting it to be readily held in the hand and of a length enabling one end to be set against the work, and, while thus held, to be struck on the other end with a hammer. 70 The end which is to be struck with a hammer is preferably provided with a heavy sole leather face *b*, and the opposite end of the block has a V-shaped notch formed therein, the bottom *c* or medial line of which extends 75 midway of the block in a convex curve, as shown in Fig. 3. A pair of oppositely disposed faces *d* are thus formed, which extend divergently from the middle line, or their line of intersection at *c*. The angular relation between said faces, at certain points, is made to correspond to the desired slope 80 of the opposite portions of the shoe shank, the surfaces forming said faces being convexly curved, or rounded in all directions, 85 that is they are convexly curved in directions both transversely of the medial line *c* and parallel thereto.

The middle portions of the surfaces, or the portions adjacent the middle portion of 90 the surface line which is perpendicular to the middle line *c*, at the middle thereof, is the only portion which, in practice, is usually engaged with the work and, when forced against the edge portion of the sole, at the 95 shank, will cause a correspondingly shaped depression therein, as indicated in Fig. 7, so that if a portion of the sole-edge is struck 100 a series of blows, the effect will be, the sole being in temper at the time, to lengthen out the portion engaged. The relative disposition of the faces *d* is such that they may be simultaneously engaged with opposite edge portions of the sole, in the shank portion, as indicated in Figs. 5 and 6, without engaging 105 the middle portion. As the shank portion usually increases in width, as it extends from the heel, it will be apparent that, if the tool is held in a middle position transversely of the shank, as indicated, the portion of the 110

faces which will engage the sole will be at varying distances from the middle of the notch corresponding to the width of the sole portion engaged.

5 To enable the V-formation in the shank of the sole to be sharply defined and accurately placed, a stiffening rib or strip X, which is V-shaped in cross section, is attached to the side of the shank stiffener y next the sole in such a position that the apex of the V extends approximately in the longitudinal middle line thereof, as indicated in Fig. 5, so that the sole may be bent longitudinally over the apex of the rib, as 10 indicated in Fig. 6.

15 In using the tool, therefore, the operator sets it in position, astride the shank portion of the shoe, so that opposite shank-edge- portions are simultaneously engaged, as 20 shown in Fig. 5, and then he strikes the leather faced end one or more sharp blows with a hammer, so that both side portions of the sole will be forced against the last bottom, as shown in Fig. 6, bending the sole 25 over the rib X, and, at the same time, lengthening the sole edge-portion, by forcing the rounded faces d into the sole, as indicated in Fig. 7. This operation is 30 repeated at closely adjacent points throughout the length of the shank, so that the entire shank edge portion will be sufficiently lengthened to cause it to stay in position in close engagement with the last bottom.

35 The sole shank portion is thus shaped so that the side portions slope sharply from the middle longitudinal line of the shank and will retain this shape indefinitely, but an important factor in thus shaping of the shank portion, so that it will retain its 40 shape, is the simultaneous action of the convex faces of the tool on the opposite sole edge portions of the shank, at a succession of points throughout the length thereof, as previously described. As thus shaped, the 45 stiffness of the sole is greatly increased in the shank.

50 As the driving action will tend to split the wood of which the tool is constructed, rivets e and f are preferably extended there-

While hard wood is preferable as a material of which to construct the tool, as it is light to handle, the same results may be secured if it is made of metal.

55 I claim:

1. A shoe shank former having a notch therein providing a pair of oppositely disposed and divergently extending faces, the surfaces thereof being convexly curved in directions parallel to the meeting line of 60 said faces, and adapted for simultaneous engagement with the opposite edge portions of the shank portion of a shoe sole, throughout a relatively small portion of the length thereof.

65 2. A shoe shank former having a V-shaped notch therein to provide a pair of divergently and oppositely disposed engaging faces, said faces being convexly curved in all directions and arranged for simultaneous 70 engagement with opposite edge portions of the shank portion of a shoe, throughout a minor portion only of the length thereof.

75 3. A shoe shank former having a face at one end adapted to be engaged by a hammer, and a V-shaped notch in the opposite end, the sides of said notch providing faces arranged for engagement with minor portions 80 only of the length of the opposite edge- portions of the shoe shank and said faces being convexly curved in directions parallel to, and transversely of the middle line of the notch.

85 4. A shoe shank former having a pair of intersecting, sole-edge-engaging faces arranged to extend divergently from their line of intersection, and said faces being convexly curved in directions parallel to said line and having corresponding portions 90 thereof arranged for simultaneous engagement with minor sections of the length of the opposite edge- portions of the shank portion of the sole, without engagement of the intermediate portions thereof, to increase 95 the length of said edge portions and simultaneously force the same into intimate relation with the bottom of the last.

In testimony whereof, I have signed my name to this specification.

CHARLES R. TOWLE.
